UNITED STATES PATENT OFFICE.

VICTOR YORK, OF ARDMORE, OKLAHOMA.

ROTARY SWIVEL.

1,357,430.

Specification of Letters Patent.

Patented Nov. 2, 1920.

Application filed June 1, 1920. Serial No. 385,792.

To all whom it may concern:

Be it known that I, VICTOR YORK, a citizen of the United States, residing at Ardmore, county of Carter, and State of Oklahoma, have invented a new and useful Improvement comprising the Rotary Swivel, of which the following is a specification.

My invention relates to the art of drilling oil wells by the so called rotary system in which a string of pipe is suspended by a cable from the top of the derrick being simultaneously rotated and fed with mud-laden fluid at its upper end.

The principal object of my invention is to provide a swivel by which such a string of pipe may be supported and simultaneously fed with mud-laden fluid under pressure.

Referring to the drawing which is for illustrative purposes only,

Figure 1 is a side elevation partly in section of my invention.

Fig. 2 is a section on a plane represented by the line 2—2 of Fig. 1.

Fig. 3 is a section on a plane represented by the line 3—3 of Fig. 1.

In the embodiment of the invention shown, 11 is the upper end of the drill pipe secured by means of a collar 12 on a body 13, this body being expanded to form an oil chamber 14 which is provided with a flange 15 upon which a cap 16 is secured by a flange 17 and bolts 18. Secured in the central passage 19 of the body 13 is a body tube 20, this tube extending up and surrounding a goose neck tube 21 which projects downwardly therein, a packing 22 compressed by a gland being provided to make a tight mud stuffing box between the tubes 20 and 21 so that pressure may be maintained thereon.

The goose neck tube 21 is provided with a goose neck 23 connected by means of a union 24 with a nipple 25 to which a pressure hose, not shown, is secured. The goose neck tube is provided with a collar 26 which is engaged by a yoke 27 which is threaded on the tube 21 and which extends down and is threaded upon a hanger 28. A packing 29 compressed by a gland 30 is provided between the hanger 28 and the body tube 21 forming what may be termed an upper oil stuffing box. The hanger 28 extends

through the cap 16, packing 35 compressed by gland 36 making an oil tight joint between the cap 16 and the hanger 28, parts 35 and 36 forming what may be termed a

lower oil stuffing box. The hanger 28 is provided with a flange 40 upon which roller bearings 41 are placed. These roller bearings support the cap 16. In practice the chamber 14 is filled with oil which is held in place by means of the upper and lower oil stuffing boxes. The whole device is supported by means of an elevator which is placed about the hanger 28, below the yoke 27 and above the gland 36, this elevator being shown diagrammatically in dotted lines at 50. In practice the device is suspended on this elevator which is in turn hung from a wire rope or cable running over the crown sheave of the derrick. The hanger 28, the yoke 27, the goose neck tube 21 and the goose neck 23 are stationary, the remainder of the apparatus shown being rotated by the rotary table not shown which engages the pipe 11. The chamber 14 being filled with oil so that the parts are well lubricated, mud is forced through the gooseneck 23 and the tube 21 into the body tube 20 and downwardly through the central passage 19 in the body 13 and into the drill pipe 11.

I claim as my invention:

1. In a swivel for supporting a string of drill pipe; a body to which said drill pipe is secured, said body having a passage connecting with said drill pipe; a body tube secured in gas tight relationship in said body and forming a continuation of said passage; a gooseneck tube projecting into the top of said body tube; a mud stuffing box making a tight joint between said body tube and said gooseneck tube; means for delivering a mud laden fluid to the top of said gooseneck tube; a hanger surrounding said body tube; an upper oil stuffing box making an oil tight joint between said hanger and said body tube; a cover secured in oil tight relationship to said body and surrounding said hanger; a lower oil stuffing box making an oil tight joint between said cover and said hanger; a flange formed on said hanger inside an oil chamber formed by said cover and said body; friction reducing means, for supporting the weight of the drill pipe, between said flange and said cover; and means for rigidly connecting said gooseneck tube to said hanger.

2. In a swivel for supporting a string of drill pipe; a body to which said drill pipe is secured said body having a passage connecting with said drill pipe; a body tube

secured in gas tight relationship in said body and forming a continuation of said passage; a gooseneck tube projecting into the top of said body tube; a mud stuffing box 5 making a tight joint between said body tube and said gooseneck tube; means for delivering a mud laden fluid to the top of said gooseneck tube; a hanger surrounding said body tube; a cover secured in oil tight relationship to said body and surrounding said 10 hanger; a flange formed on said hanger inside an oil chamber formed by said cover and said body; friction reducing means, for supporting the weight of the drill pipe, between said flange and said cover; and means for rigidly connecting said gooseneck tube to said hanger.

3. In a swivel for supporting a string of 20 drill pipe; a body to which said drill pipe is secured, said body having a passage connecting with said drill pipe; a body tube secured in gas tight relationship in said body and forming a continuation of said passage; a gooseneck tube projecting into the top of 25 said body tube; a mud stuffing box making a tight joint between said body tube and said gooseneck tube; means for delivering a mud laden fluid to the top of said gooseneck tube; a hanger surrounding said body tube; an 30 upper oil stuffing box making an oil tight joint between said hanger and said body tube; a cover secured in oil tight relationship to said body and surrounding said hanger; a lower oil stuffing box making an oil tight 35 joint between said cover and said hanger; a flange formed on said hanger inside an oil chamber formed by said cover and said body; friction reducing means, for supporting the weight of the drill pipe between 40 said flange and said cover; and a yoke rigidly connecting said gooseneck tube with said hanger.

4. In a swivel for supporting a string of 45 drill pipe; a body to which said drill pipe is secured said body having a passage connecting with said drill pipe; a body tube secured in gas tight relationship in said body and forming a continuation of said passage; a gooseneck tube projecting into the top of 50 said body tube; a mud stuffing box making a tight joint between said body tube and said gooseneck tube; means for delivering a mud laden fluid to the top of said gooseneck tube; a hanger surrounding said body tube; a cover secured in oil tight relationship to 55 said body and surrounding said hanger; a flange formed on said hanger inside an oil chamber formed by said cover and said body; friction reducing means, for supporting the weight of the drill pipe, between 60 said flange and said cover; and a yoke rigidly connecting said gooseneck tube with said hanger.

5. In a swivel for supporting a string of

drill pipe; a body to which said drill pipe 65 is secured, said body having a passage connecting with said drill pipe; a body tube secured in gas tight relationship in said body and forming a continuation of said passage; a goose-neck tube projecting into 70 the top of said body tube; a mud stuffing box making a tight joint between said body tube and said gooseneck tube; means for delivering a mud laden fluid to the top of said gooseneck tube; a hanger surrounding said 75 body tube; an upper oil stuffing box making an oil tight joint between said hanger and said body tube; a cover secured in oil tight relationship to said body and surrounding said hanger; a lower oil stuffing box making 80 an oil tight joint between said cover and said hanger; a flange formed on said hanger inside an oil chamber formed by said cover and said body; a roller bearing between said flange and said cover and around said 85 hanger; and means for rigidly connecting said gooseneck tube to said hanger.

6. In a swivel for supporting a string of 90 drill pipe; a body to which said drill pipe is secured, said body having a passage connecting with said drill pipe; a body tube secured in gas tight relationship in said body and forming a continuation of said passage; a gooseneck tube projecting into the top of 95 said body tube; a mud stuffing box making a tight joint between said body tube and said gooseneck tube; means for delivering a mud laden fluid to the top of said gooseneck tube; a hanger surrounding said body tube; a cover secured in oil tight relationship to said body and surrounding said hanger; a flange formed on said hanger inside an oil chamber formed by said cover and said body; a roller bearing between said 100 flange and said cover and around said hanger; and means for rigidly connecting said gooseneck tube to said hanger.

7. In a swivel for supporting a string of 110 drill pipe; a body to which said drill pipe is secured, said body having a passage connecting with said drill pipe; a body tube secured in gas tight relationship in said body and forming a continuation of said passage; a gooseneck tube projecting into the top of 115 said body tube; a mud stuffing box making a tight joint between said body tube and said gooseneck tube; means for delivering a mud laden fluid to the top of said gooseneck tube; a hanger surrounding said body tube; an upper oil stuffing box making an oil tight 120 joint between said hanger and said body tube; a cover secured in oil tight relationship to said body and surrounding said hanger; a lower oil stuffing box making an oil tight joint between said cover and said hanger; a flange formed on said hanger inside an oil chamber formed by said cover and said body; a roller bearing between said 125 hanger; and means for rigidly connecting said gooseneck tube to said hanger.

flange and said cover and around said hanger; and a yoke rigidly connecting said gooseneck tube with said hanger.

8. In a swivel for supporting a string of
5 drill pipe; a body to which said drill pipe
is secured, said body having a passage con-
necting with said drill pipe; a body tube
secured in gas tight relationship in said
body and forming a continuation of said
10 passage; a gooseneck tube projecting into
the top of said body tube; a mud stuffing
box making a tight joint between said body
tube and said gooseneck tube; means for de-
livering a mud laden fluid to the top of said

gooseneck tube; a hanger surrounding said 15
body tube; a cover secured in oil tight rela-
tionship to said body and surrounding said
hanger; a flange formed on said hanger in-
side an oil chamber formed by said cover
and said body; a roller bearing between said 20
flange and said cover and around said
hanger; and a yoke rigidly connecting said
gooseneck tube with said hanger.

In testimony whereof, I have hereunto set
my hand at Ardmore, Oklahoma, this 21st 25
day of May, 1920.

VICTOR YORK.
